STORAGE AND SHIPPING TRAY FOR CONTAINERS

Edward F. Joyce 3rd, Boonton, N. J.

Application June 20, 1957, Serial No. 46,669

Term of patent 3½ years

(Cl. D58—13)

Des. 184,354

PAGE 2

Fig. 3

I claim:

The ornamental design for a storage and shipping tray for containers, substantially as shown.
